UNITED STATES PATENT OFFICE.

WILLIS R. KING, OF NEWARK, NEW JERSEY, ASSIGNOR TO THE HANSON & VAN WINKLE COMPANY, OF NEW JERSEY.

ELECTRICAL RESISTANCE-BOARD.

SPECIFICATION forming part of Letters Patent No. 664,953, dated January 1, 1901.

Application filed July 21, 1900. Serial No. 24,416. (No model.)

To all whom it may concern:

Be it known that I, WILLIS R. KING, a citizen of the United States, residing at Newark in the county of Essex and State of New Jersey, have invented certain new and useful Improvements in Electrical Resistance-Boards; and I do hereby declare the following to be a full, clear, and exact description of the invention, such as will enable others skilled in the art to which it appertains to make and use the same, reference being had to the accompanying drawings, and to numerals of reference marked thereon, which form a part of this specification.

15 This invention has reference to improvements in electrical resistance-boards to be employed in connection with dynamo-electric machines and for various other electrical purposes and which are intended for regulating the intensity of the electric current.

20 My present invention has for its principal objects, first, to provide a circular or other suitably-shaped resistance-board of a large range having electrically-divisible resistances, preferably in the form of coils, made independently of and separable from suitable receiving-sockets or other holding means with which the resistances are connected; second, to provide a novel construction which will 25 admit of making the combined electrical sections of the resistance-coils mechanically in one or more pieces for the purpose of forming more perfect electrical connections and resistances of the parts when more than one 30 section is used; third, to form a pivot-support of the switch-arm integrally with one of the insulated contact-making segments of the board, and, finally, to provide a novel construction of electrical resistance-board which 35

40 shall be of a simple construction and to provide a device of the character hereinafter set forth in which the resistance capacity of the mechanism is very easily and quickly changed by varying the diameters and lengthening or 45 shortening the resistance-coils or by varying the material of the resistances, and furthermore, by increasing or decreasing the number of resistances or coils, all of which will be more fully set forth in the accompanying 50 description of my invention.

This invention therefore consists in the

novel construction of electrical resistance-board to be hereinafter fully described and also in the several novel arrangements and combinations of the various parts thereof, all 55 of which will be fully set forth in the accompanying specification, and then finally embodied in the clauses of the claim.

The invention is clearly illustrated in the accompanying drawings, in which—

60 Figure 1 is a plan or top view of one form of electrical resistance-board embodying the principles of my invention, and Fig. 2 is a front edge view of the same. Fig. 3 is a vertical section of the said device, taken on line 65 33 in said Fig. 1. Fig. 4 is a bottom view of the same, and Fig. 5 is a vertical cross-section taken on line 55 in said Fig. 1. Fig. 6 is a plan or top view of an electrical resistance-board of a modified form of construction, but still embodying the principal elements of this invention; and Fig. 7 is a cross-section of the same, taken on line 77 in said Fig. 6.

70 Similar numerals of reference are employed 75 in all of the said above-described views to indicate corresponding parts.

In the said drawings in Figs. 1 to 5, inclusive, 1 indicates the main table or base, which may be circular in outline, but may be of any 80 other preferred shape, and is preferably provided with the leg portions or a surrounding flange 2, in which there are holes or openings 3 for the reception of screws or other suitable means for securing the device in position. The said table or base has a central opening in which is arranged a central stud or post 4, rotatively placed in an insulating collar or sleeve 5 in said central hole or opening of the said table or base 1. Against the 85 under surface of the said main table or base 1 I have suitably secured a disk or plate 6 of an insulating material, and upon its upper surface is another disk or plate 7, also made of insulating material. Suitably secured upon the upper insulating disk or plate 7, preferably by means of screws 8, which, as will be seen from Fig. 5, pass through the two insulating-disks 6 and 7 and through the main body table or base 1 of the device, but which 90 are insulated therefrom by means of the sleeves or collars 9, is a circular metallic con-

tact-ring 10. This ring is provided with a segmental projection 11, in which there is a radially-arranged receiving-socket 12 and set-screws 13 for receiving and securing in said socket the end of one of the electrical main wires in which the electrical resistance-board is to be placed in circuit. The said central stud or post 4, hereinabove mentioned, is securely held in position by means of an enlargement 14, forming a part of said post, resting upon the insulated disk 7, and a nut 17, screwed upon the lower screw-threaded end portion 18 of the said post, substantially as illustrated in Figs. 3 and 5. The said post 4 is also provided above the said portion 14 with a cylindrical part 15, which is arranged in a hole 20 in a contact-making switch-lever 19 and is rotatively arranged upon the parts 14 and said portion 15, as will be clearly seen. The said switch-lever is properly held in place, so as to cause its contact-surfaces 21 and 22 to make proper sliding contact, as hereinafter more fully set forth, by a suitably-constructed spring-plate 23 and a nut 24, screwed down upon the screw end 16 of the post or stud 4, so as to compel the free ends of the said spring-plate to exert sufficient pressure against the upper surface of the switch-lever 19 and to make the proper electrical contact of its parts with the ring 10 and certain series of metallic section-blocks or contact-sections 25, which are arranged in a circle around the said ring 10, but are separated from said ring by a space 26, and are also separated from themselves by radiating spaces 27, substantially as represented in Fig. 1. The said switch-lever 19 is thus movably arranged above said ring 10, its part 21 being at all times in sliding contact with the upper surface of said ring when turned by means of the finger-piece or handle 28 while in its initial position. When there is no current passing through the device, its part 22 rests upon the upper surface of the segmental projection 11; but when the lever is moved then the said part 22 can be brought in electrical contact with any one of the said metallic section-blocks or contact-sections 25 to establish an electrical circuit through the several parts of the device in the manner to be presently described.

The blocks or segments, of which there may be any desirable number, according to the size of the apparatus and the purposes to which it is to be put, are separated from each other, as stated, by small intervening spaces 27 and are secured to the non-conducting disk or plate 7 by means of screws 29, which are insulated from the table or base 1 by the insulating collars or sleeves 30. Radiating from each of the said segments or blocks 25 is a socket 31, and attached to and extending from or near the outer extremity of each socket to the next adjoining socket 31 of the adjacent block 25 and secured in said sockets by means of the screws 32 are the ends 33 of a section-coil of resistance-wire or other suit-

able resistance 34. All of the sockets 31 are what may be termed "double" sockets for receiving the respective ends of the adjacent coils; but the two end sections of blocks 25 are provided with "single" sockets 31, since in these sockets are arranged but one end of the first and last resistance-coils, as will be clearly evident from an inspection of Fig. 1 of the drawings. The last block or segment 25 is also provided with a radially-arranged projection 35, which has a socket 36 and set-screws 37 for securing in said socket the end of the other electric main wire in which the electrical resistance-board is placed in circuit.

Having thus described the construction of my invention represented in Figs. 1 to 5, inclusive, its operation is as follows: The socketed portions 11 and 35 of the ring 10 and last section or block 25, respectively, having been connected by means of the main electric wires in the ordinary manner with any source of electricity a complete circuit will be established through the apparatus hereinabove described. The switch-arm 19, as will be evident, can be turned in any desired position, whereby contact is produced between the ring 10 and any one of the blocks 25, and in consequence thereof any one or more resistance-coils 34 can be cut in or out of the main circuit, as will be clearly evident from an inspection of the several figures of the drawings. From an inspection of Fig. 1 it will be seen that the diameters of the various resistance-coils may be varied, whereby the resistance capacity of this mechanism is very easily and cheaply changed to meet the conditions existing for different work with which the resistance-board is to be used. It will also be evident that the number of sections or blocks 25 and the sockets connected therewith may be changed by adding to or taking away from the number of blocks herein shown without changing the nature of my invention, and the material of which the resistances are made may be varied, if desired.

In lieu of the arrangement and construction of the several parts just described in connection with said Figs. 1 to 5, inclusive, I may employ the form of resistance-board represented in Figs. 6 and 7 of the drawings. In this construction the base is indicated by the reference-number 38, and it is made of insulated iron, slate, or marble or any other suitable material, and 39 represents a series of metallic section blocks or segments which are disposed in a circle and are secured upon said base by means of screws 40, being held in position by nuts 41 on the under side of the base, as shown in Fig. 7. Radiating from each block 39 is a socket 42, attached to and extending from or near the outer extremity of each block to the next adjoining block, and the said sockets are connected by means of the resistance-coils 43, as and in the manner hereinabove set forth, and are preferably held in place by means of set-screws 43. These coils connect all the several blocks 39 except

the block 39' and the block 39'', to the latter of which is secured, by means of a bolt 44 and a nut 45, a socket 46 for the end of one of the main electric wires in which the said resistance-board is to be connected in circuit. Between the first segment 39' and the last segment 39'' is a segment 47, which has a forwardly-extending portion 48, to which is secured, by means of a bolt 49 and nut 50, a socket 51 for the reception of the end of the other main electric wire in which the device is to be arranged in circuit. The said segment or block 47 is also provided with an inwardly-extending portion 52 and has central 15 stud portions 53 and 54, as illustrated in Fig. 7. The portion 53 is arranged in a central hole and is insulated therefrom by means of a washer 56 of a non-conducting material, and rotatively secured upon the part 54 by 20 means of a nut 57 or in any other suitable manner is a switch-lever 58, provided with a finger-piece or handle 59. Said lever in this case is provided with suitable contact brush or brushes 60, which are suitably secured to 25 said lever by means of a screw or screws 61 and can be brought in electrical contact with any one of the said segments or blocks 39 or 39' or 39''. In this manner a complete circuit can be established through the socket 51 with 30 the block 47 and its inwardly-extending portion 52 with the stud 54 and then by means of the lever 58 and the brush or brushes 60 with any one of the blocks 39 to cut in or out 35 one or more of the resistance-coils 34 or other resistance material employed in the manner hereinabove described in connection with the construction represented in said Figs. 1 to 5, inclusive. It will also be evident that in the form of resistance-board represented in said 40 Figs. 6 and 7 any number of such blocks or segments 39 may be employed, and it will be further observed that the resistance capacity of this mechanism may be changed by varying the diameters of the coils or by lengthening 45 or shortening the resistance-coils, which are inserted in the sockets in the outer faces of the segments or blocks, and the material of which the resistances are made may also be varied at will.

50 I am fully aware that changes may be made in the several arrangements and combinations of the parts without departing from the scope of my present invention. Hence I do not limit my invention to the exact arrangements and 55 combinations of the parts as herein described, and illustrated in the accompanying drawings, nor do I confine myself to the exact details of the construction of the said parts.

Having thus described my invention, what 60 I claim is—

1. A resistance-board, comprising an arrangement of segments or blocks, having intervening spaces between them, a non-conducting support on which said segments or blocks are arranged, an outwardly-projecting 65 socket on each segment or block, a sectional resistance-coil provided with free end por-

tions arranged in the adjacent sockets of said segments or blocks, so as to connect two adjacent sockets, and a centrally arranged and pivoted switch-lever, adapted to make electrical contact with either of said segments or blocks, substantially as and for the purposes set forth. 70

2. A resistance-board, comprising a non-conducting base, segments or blocks secured thereto, disposed in a circle around a common center, sockets extending radially from said segments or blocks, and resistance material or coils, integrally separate from and removably connected with said sockets, in combination, with a centrally-pivoted switch arm or lever arranged to make electrical contact with either one of the said segments or blocks, substantially as and for the purposes set forth. 75

3. A resistance-board, comprising a non-conducting base, segments or blocks secured thereto, disposed in a circle around a common center, sockets extending radially from said segments or blocks, and one or more helical resistance-coils, integrally separate from and removably connected with said sockets, in combination, with a centrally-pivoted switch arm or lever, electrically connected at its one end with the main circuit, and adapted to make electrical contact at its other end with either of said segments or blocks, substantially as and for the purposes set forth. 90

4. A resistance-board, comprising a non-conducting base, segments or blocks secured thereto, disposed in a circle around a common center, a centrally-arranged vertical post in said base provided with a vertically-arranged screw-threaded portion, sockets extending 105 radially from said segments or blocks, one or more helical resistance-coils, integrally separate from and removably connected with said sockets, in combination, with a centrally-pivoted switch arm or lever, electrically connected at its one end with the main circuit, and adapted to make electrical contact at its other end with either of said segments or blocks, a nut placed upon the screw end of 110 said vertical post, and an expansible spring 115 on said post between the said nut and said switch-lever, substantially as and for the purposes set forth. 115

5. A resistance-board, comprising a non-conducting base, segments or blocks secured 120 thereto, disposed in a circle around a common center and one of said segments being extended toward the center, sockets extending radially from said segments, and resistance material or coils integrally separate from and 125 removably connected with said sockets, in combination, with a switch arm or lever, electrically connected at one of its ends with the main circuit, and adapted to make electrical contact at its other end with either of said segments, substantially as and for the purposes set forth. 130

6. A resistance-board, comprising a non-conducting base, segments or blocks secured

thereto, disposed in a circle around a common center and one of said segments being extended toward the center, sockets extending radially from said segments, and resistance-coils integrally separate from and removably connected with said sockets, said coils being of varying diameters and varying lengths, in combination, with a switch arm or lever, electrically connected at one of its ends with the main circuit, and adapted to make electrical

contact at its other end with either of said segments, substantially as and for the purposes set forth.

In testimony that I claim the invention set forth above I have hereunto set my hand this 19th day of July, 1900.

WILLIS R. KING.
